Primary Examiner — Susan Moon Lee*(74) Attorney, Agent, or Firm* — Edna M. O'Connor; Gregory W. O'Connor**(57) CLAIM**

The ornamental design for a fashion scarf for dogs or cats, as shown and described.

DESCRIPTION

FIG. 1 is a right front perspective view of a fashion scarf for dogs or cats showing my new design.

FIG. 2 is a right side elevational perspective view thereof.

FIG. 3 is a left side elevational perspective view thereof.

FIG. 4 is a front elevational perspective view thereof.

FIG. 5 is a back elevational perspective view thereof.

FIG. 6 is a top perspective view thereof.

FIG. 7 is a right front perspective view of a second embodiment of a fashion scarf for dogs or cats showing my new design.

FIG. 8 is a right side elevational perspective view thereof.

FIG. 9 is a left side elevational perspective view thereof.

FIG. 10 is a front elevational perspective view thereof.

FIG. 11 is a top perspective view thereof.

FIG. 12 is a back elevational perspective view thereof.

FIG. 13 is a right front perspective view of a third embodiment of a fashion scarf for dogs or cats showing my new design.

FIG. 14 is a right side elevational perspective view thereof.

FIG. 15 is a left side elevational perspective view thereof.

FIG. 16 is a front elevational perspective view thereof; and,

FIG. 17 is a top perspective view thereof.

Portions shown in broken lines are not claimed.
